CORN PAD

William M. Scholl, Chicago, Ill.

Application September 28, 1933, Serial No. 691,297

1 Claim. (Cl. 128—153)

This invention relates to calli treatment pads and mounting therefor, and more particularly to a composite article of manufacture embodying plasters for the treatment of calli and the like which are adapted to be applied in interfitted relation to the surface to be treated.

It has heretofore been the practice to sell to the trade calli treatment pads each of which has an enclosed centrally disposed opening in which may be disposed a piece of medicament such, for example, as a salicylic medicament for the treatment of the calli. The salicylic acid was usually sold attached to a base of gauze or crinoline from which it was necessary to cut a small piece of such size as would fit in the opening on the underside of the pad.

This practice has not proven satisfactory for the reason that in the first place no protective covering was provided for the salicylic acid and as a result it deteriorated or crystallized out and thus lost its strength before it was put into use, and in the second place it required that the user go to the trouble of cutting out a piece of medicated material of such size as would fit in the corn pad proper as noted hereinabove.

In other words, no carrier was provided for the medicament or salicylic acid which could be removably stuck to a gauze or crinoline base whereby all that was necessary was for the customer to simply remove the carrier with the medicament thereon from the base and to apply it to the corn under the corn pad or plaster.

It is therefore an object of this invention to provide in a plaster for the treatment of calli or the like a carrier for a medicament such as salicylic acid which not only affords a means for enabling salicylic acid to be removably supported on a base of gauze or crinoline, but in addition thereto provides a protective covering for the salicylic acid whereby deterioration of the salicylic acid prior to its use will be materially lessened.

Another object of the invention has to do with the provision of a calli treatment plaster having a filler which provides the plaster with an impervious barrier as far as the passage of matter from the interior to the exterior of the plaster is concerned whereby the plaster will not become unsightly or adhere to the hose or garment of the wearer.

In accordance with the general features of this invention, there is provided a composite article of manufacture for the treatment of calli and the like, which includes a gauze or crinoline base having one or more corn pads removably stuck thereon each of which includes a wall of fabric coated

with adhesive on its underside and having a central opening and an outer covering over said opening and secured to the wall, and one or more medicated tabs removably stuck on the same gauze or crinoline base. The outer covering of the pad and the tab each include a layer of fabric having therein a filler impervious to the passage of the ingredients of the pad and tab therethrough. Furthermore, the single layer tab is of such size that upon its removal from the base it may be disposed in the central opening of the pad when the pad is applied to a surface to be treated; the layer of the tab serving as both a protective covering and carrier for a coating of medicament such as salicylic acid on its under side.

Another feature of the invention relates to the application of the filler to the fabric layer of the plaster which filler is preferably a rubber compound vulcanized to the fabric layer to cause it to penetrate through the mesh of the fabric.

Other objects and features of this invention will more fully appear from the following detail description taken in connection with the accompanying drawing which illustrates a single embodiment thereof and in which

Figure 1 is a plan view of the composite article of manufacture for the treatment of calli and the like embodying the features of this invention.

Figure 2 is an enlarged cross-sectional view taken on substantially the line II—II of Figure 1 looking in the direction indicated by the arrows.

Figure 3 is an enlarged sectional view taken on substantially the line III—III of Figure 2 looking in the direction indicated by the arrows and illustrating the construction of the salicylic acid tab.

Figure 4 is an enlarged sectional view taken on the line IV—IV of Figure 2 looking in the direction indicated by the arrows and illustrating the impregnation of the outer fabric layer of the corn pad with a filler, which filler is disposed on the underside of the fabric and is coated with an adhesive.

Figure 5 is an enlarged view of one of the corn pads of my invention showing it applied to a corn.

Figure 6 is a cross-sectional view taken on the line VI—VI of Figure 5 and clearly illustrating the interfitting relationship of the salicylic acid tab and the corn pad or plaster.

The reference character 10 designates generally a gauze or crinoline base which is of the usual woven mesh construction. Removably stuck to this base 10 on one or more corn pads 11 and one or more medicated or salicylic acid tabs 12. It is of course to be appreciated that while I have

illustrated the crinoline base 10 as having applied thereto twelve pads 11 and twelve tabs 12, the invention is not to be thus limited since the base may be made to carry any desired number of such 5 tab and pad plasters.

Each of the pads 11 as best shown in Figure 2 embodies a wall 15 of fabric coated on its under side with adhesive 16. This wall 15 is made of a plurality of laminations which may be cemented 10 or vulcanized together as desired. The wall 15 is of an oval shape and defines a central opening 17 which is covered by a top layer 18 secured to the top side of the wall 15.

The top or outer layer 18 includes a piece of 15 fabric 20 which has its under side provided with a filler 21 for rendering the fabric 20 impervious to the passage of the ingredients of the pad therethrough. The filler 21 comprises a rubber adhesive mass which is vulcanized on the fabric 20 20 so as to cause the mass to penetrate the fabric and to be thoroughly secured to the fabric. The outer surface of the fabric 20, however, remains uncoated and hence has the appearance of the natural fabric.

25 In order to secure this outer layer 18 to the wall 15, the under side of the coated or filled surface of the fabric 20 has a coating of adhesive material 22 as shown in Figure 4.

In the manufacture of the adhesive outer layer 30 18, I first spread the mixture of waterproofing material or filler 21 upon the fabric 20 by any suitable means such as the spreader knife or calender roll.

The filler 21, which should contain rubber, is 35 next vulcanized by any ordinary process of vulcanization so as to cause it to be made an integral part of the fabric 20. Either a heat cure or an air cure may be used.

40 The adhesive coating 22 is then spread, while in a suitable solvent, upon the under surface of the filled fabric layer, after which the solvent is allowed to dry. Heat may or may not be used as desired.

The rubber filler mass comprising the coating 45 21 may be made up of a suitable rubberized compound containing substances such as oxide of zinc, lithopone or other minerals which serve as fillers in sealing the mesh of the fabric and which would be reinforced by the rubber content 50 of the compound.

55 It should also be noted that the coating of the outer fabric layer with a filler does not in any way interfere with the flexibility of the top covering layer 18 and that layer may be bowed inwardly as shown in Figure 2 or may be flexed to conform with the contour of the surface to which the pad is applied as shown in Figures 5 and 6.

60 Each of the medicated or salicylic acid tabs 12 embodies a carrier in the form of a circular disc of fabric 25 (Figure 3) which has applied to its under surface a filler 21' vulcanized to the fabric 25 so as to become an integral part thereof. This filler 21' may be similar to the filler 21. The filled surface of the fabric 25 also has applied to it a coating 26 having an adhesive characteristic so as to be capable of being stuck to the crinoline base 10 or to the surface to be treated and embodying a medicament such as salicylic acid.

65 Now it will be evident from Figure 3 that the layer of fabric 25 of the medicated plaster or

tab 12 serves both as a protective covering and carrier for the coating of medicament 26 on its under side. This is advantageous as noted hereinabove in that the protective coating materially retards disintegration of the medicament or salicylic acid coating 26 whereby the strength of that coating will be preserved for the medical treatment of the corn.

5 Moreover, as is evident from Figure 6 the barrier afforded by the filler 21' of the tab 12 10 aids to prevent the salicylic acid from leaving the tab and penetrating the under surface of the outer layer 18 of the pad 11 when the tab is disposed under the pad.

Now in the use of my composite article of 15 manufacture, the user first removes one of the tabs 12 from the crinoline base 10 by simply pulling it off the base and then applies it to the part to be treated such, for example, as a corn 30 by sticking it on the corn with the salicylic acid 20 coating 26 in contact with the outer surface of the corn.

Thereafter the user pulls one of the plaster pads 11 from the crinoline base 10 and places it over the medicated tab 12 as shown in Figures 5 25 and 6. Inasmuch as both the pad and the tab are flexible, it of course follows that they may be readily bent to conform with the outer contour of the part to which they are applied as is also evident from Figures 5 and 6.

I of course desire it understood that while I 30 have described the medicament coating 26 as preferably embodying salicylic acid it is of course to be understood that any other suitable medicament may be used in lieu of the salicylic acid.

35 Furthermore, it should be noted that while I have illustrated the corn pads 11 as being of an oval shape and the tabs 12 as being of a circular shape, these plasters may be made of other desirable shapes without deviating from the spirit of 40 this invention.

I claim as my invention:

A composite article for the treatment of calli and the like, including a pair of members of different sizes, each of said members being in 45 the form of a pad and each having a backing element of fabric the undersurface of which is impregnated with a filler impervious to medicaments used in calli treatment, the outer surface of the fabric being uncoated and in its natural 50 state, the smaller of said members having a medicament on the undersurface thereof, the larger of said members having a coating of adhesive on the undersurface of said impervious filler, and a cushioning element on said coating of adhesive 55 and having a recess therein housing the smaller of said members, said cushioning element also having an undercoating of adhesive, whereby the clean outer surface of the backing of the smaller member adheres to the adhesive coating of the 60 backing of the larger member to hold the composite article in place and the clean outer surface of the backing of the larger member will remain free from the clothing of a user, said members being adapted for merchandizing as 65 separable units because the impervious coating on the smaller member is adapted to protect said member against deterioration of its medicament.

WILLIAM M. SCHOLL.
